(57) **CLAIM**

The ornamental design for a modular cat station, as shown and described.

DESCRIPTION

FIG. 1 is a front perspective view illustrating our design for a modular cat station;

FIG. 2 is a front view thereof;

FIG. 3 is a rear view thereof;

FIG. 4 is a top view thereof;

FIG. 5 is a left side view thereof;

FIG. 6 is a bottom view thereof;

FIG. 7 is a right side view thereof; and,

FIG. 8 is a bottom perspective view thereof.

The broken lines in the drawings are for illustrative purposes only and form no part of the claimed design.

1 Claim, 7 Drawing Sheets
